CARL WASHBURN DECKER, OF CHARLES CITY, IOWA, ASSIGNOR OF TWO-THIRDS TO FRANK E. HIRSCH AND GEORGE W. VON BERG, OF CHARLES CITY, IOWA.

WINDMILL-PUMP COUPLING.

SPECIFICATION forming part of Letters Patent No. 774,939, dated November 15, 1904.

Application filed July 8, 1903. Serial No. 164,718. (No model.)

To all whom it may concern:

Be it known that I, CARL WASHBURN DECKER, of Charles City, in the county of Floyd and State of Iowa, have invented a new and useful Improvement in Windmill-Pump Couplings, of which the following is a specification.

My invention is in the nature of a device designed to be attached to any ordinary windmill-pump, its object being to provide a convenient and efficient means of coupling the hand-lever of the pump to the pump-rod, at the same time uncoupling the windmill-rod from the pump-rod, and vice versa. The means for attaining this object are embodied in a simple and compact device which is attached to a special form of windmill-rod, all the apparatus for coupling and uncoupling being contained in this pump-rod with its attachments. It is intended that the device shall be made practical and extremely convenient in that this pump-rod may be placed in the pump, replacing the original pump-rod, and after attaching the device as hereinafter described the apparatus is ready to be used.

In the accompanying drawings, Figure 1 is a front view of the special pump-rod with its attachments. Fig. 2 is a side view of the same. Fig. 3 is a front view of the rod without its attachments; Fig. 4, a side view of the same. Fig. 5 is a perspective view of the upper coupling-arm. Fig. 6 is a perspective view of the lower coupling-arm. Fig. 7 is a perspective view of a clevis-shaped loop or stirrup which is hung upon the pintle-pin of the hand-lever and co-operates with the lower coupling-lever shown in Fig. 6 to couple the hand-lever to the pump-rod. Fig. 8 is an enlarged perspective view of the buffer to be attached to the pump-rod, which buffer also serves as a guide for the upper coupling-arm and a means for attaching this coupling-arm to the pump-rod through a spring. Fig. 9 is a side view of a special form of pintle-pin and nut for the upper end of the hand-lever, said pin also serving as a means for suspending the stirrup shown in Fig. 7. Fig. 10 is a vertical longitudinal section of the windmill-rod slide. Fig.

11 is a perspective view of this slide. Fig. 12 is a side view of the entire device in position 50 on an ordinary windmill-pump. Fig. 13 is a front view of the same. Figs. 14 and 15 are vertical longitudinal sections through the lower portion of the windmill-rod slide, the pump-rod, and upper coupling-lever, showing 55 the device in position when uncoupled and coupled, respectively. Figs. 16 and 17 are detail views of a portion of the lower parts of the pump-rod and coupling-stirrup, showing the device as coupled and uncoupled, re- 60 spectively.

Referring to the drawings, Figs. 3 and 4, this special pump-rod is made to conform in general outline to the shape of the ordinary pump-rod. At its upper end it has a special 65 form of mortise A' and A''. This mortise is formed by a rabbet on one side of a slot in the middle to receive a cross-head B', the upper end of the upper coupling-arm B, as shown in Fig. 5. The pump-rod has also an 70 oblong opening at A³, constructed to receive the lug B² of the upper coupling-arm B.

The above-mentioned opening A³ of this pump-rod corresponds in position to the position of the upper round hole in the ordinary 75 windmill pump-rod. At A⁴ in the pump-rod there is constructed a slot extending from a point A⁵ upwardly. The point A⁵ corresponds in position to the position of the lower round opening in the ordinary windmill pump-rod. 80 The slot extends upward to such a distance that when the rod is in position in the pump the pin of the hand-lever may pass through this slot and allow the upper end of the hand-lever to be at a position just below the guide 85 of the pump-head when the rod A is at its lowest point of stroke while being carried by the windmill-rod slide.

A⁶ is a lateral enlargement of the slot A⁴ at its lower extremity, so designed that the middle portion of the stirrup D when held against the side X of this enlargement will couple the hand-lever to the pump-rod. 90

A⁶ is a recess in the pump-rod on its side shown in Fig. 4 and extending from the 95 front edge y to the slot A⁴.

A^7 is a notch in the edge y of the pump-rod.

A^8 is a half-round depression in the side of the pump-rod opposite to the side shown in Fig. 4, which depression is located at a short distance below the lower end of slot A^4 and is intended to provide a means for attaching the buffer F by means of a bolt and nut to said pump-rod.

10 The lower end of B , as shown in Fig. 5, has an inclined plane at B^3 , which is used to move this lower end B out from the rod A by means of the stirrup D , throwing B out of connection with the windmill-rod slide, as de-

15 scribed later. The extreme lower end of B is bent in a direction opposite to the bend B^3 and has a hole B^4 , serving as a means for attaching the spring E . (Shown in Figs. 1 and 2.)

20 The lower coupling-arm C , Fig. 6, has at its upper end a round hole C' , providing a means of pivotally attaching it to the pump-rod by means of a small set-screw C^5 . At its lower end the arm C has a hook C^2 . At C^3 25 there is an upward extension of this lower end of arm C in a direction parallel therewith. This extension is designed to rest on pump-rod A at A^7 and constitutes a spring to force arm C away from the edge y of the 30 pump-rod.

25 F , Fig. 8, is the buffer, which when attached to pump-rod A , if the rod is allowed to drop, rests on the spring H , mounted on the pump-head. The buffer F has at F' two 35 arms extending in a direction at right angles to the pump-rod A , as shown in Figs. 1 and 2, serving as a guide for the lower end of arm B . At F^2 there is a small shoulder, with a hole adapted to receive the end of the spring 40 E , the other end of which is attached to arm B at B^4 .

45 G , Fig. 9, is a pin adapted to fit loosely in any ordinary pump-handle, having at G' a notch on each side. This portion G' of pin G is intended to rest in the slot A^4 in pump-rod A . This pin has a special nut G^2 and a split key G^3 , adapted to pass through the hole G^4 in the pin and engage the depressions in the rim of nut G^2 , allowing a limited adjustment 50 of position of nut G^2 on pin G sufficient to adjust pin G and stirrup D to differences in the width of the upper end of different hand-levers.

55 Referring to Fig. 10, I' is a grooved plate, whose grooves are adapted to engage corresponding grooves on the surface of the windmill-rod slide I . These grooves are in a direction at right angles to the greatest length of the piece. At I^1 there are holes adapted to 60 receive bolts which pass through a slot I^3 in slide I and then through the lower end of the windmill-rod. These bolts, with suitable nuts, connect the parts I' and I firmly to the mill-rod; but if the nuts on bolts are loosened suffi- 65 ciently to allow the grooves on I' and I to be

disengaged the part I may be raised or lowered a considerable distance by reason of the slot I^3 , after which the nuts may be again tightened to reconnect the parts.

At I^4 in slide I there is a beveled mortise, 70 which is adapted to engage the lug B^2 in arm B . At I^5 there is a recess, also adapted to engage the lug B^2 just mentioned. As shown in Fig. 11, the part I is channeled longitudinally to slide on the rod A and has at its 75 lower end two parallel outwardly-projecting lips I^6 , serving to keep arm B in position when the apparatus is in use.

The method of applying my devices is as follows: Referring to Figs. 12 and 13, the 80 numerals 1, 2, and 3 represent the pump-head, lever-support, and hand-lever, respectively, of an ordinary windmill-pump, and 4 is the windmill-rod of an ordinary pumping-windmill. If now it is desired to place in position the attachments described, the pump-rod originally in the pump having been removed by uncoupling below the pump-head and sliding up out of guide z , the rod accompanying this device is passed through the guide 85 z from above and through the buffer F and spring H and then through the lower guide in the pump-head. My rod is then coupled below pump-head to the piston-rod of the pump. The lower coupling-arm C is next, by 90 means of the set-screw C^5 , attached to the pump-rod A at A^9 . Rod A now being forced down to its lowest position, the pintle-pin G is passed through one arm of stirrup D , D having first been passed through the slot A^4 in the 95 pump-rod, so that one arm is on each side of the rod. Pin G is then passed on through the hole in left side of the upper end of hand-lever, said hand-lever having been first brought into position embracing the pump-rod. The pin G 100 is passed on through the slot A^4 in the pump-rod and through the hole in the opposite side of upper end of hand-lever and through hole in other arm of the stirrup D . The nut G^2 and the pin G^3 may now be placed in position, 105 the pin G holding the hand-lever in position embracing pump-rod A and also the stirrup D in position embracing the hand-lever, with its lower middle part passing through slot A^4 110 in the rod A just below the upper end of hand-lever. By means of washers w , placed between stirrup D and the upper end of the hand-lever on either side, as in Fig. 13, the parts D and G can be made to accommodate 115 different sizes of hand-lever. The pump-rod 120 A being in position, the cross-head B' of upper coupling-arm B is made to engage rod A at A' and A^2 , and lug B^2 is passed into the hole A^3 of said rod. The arm B now being 125 in position attached to rod A , the spring E , by means of the holes F^2 in buffer F and B^2 in arm B , is attached to said parts F and B . Slide I is now attached to the windmill-rod 130 4 by means of plate I' , with its bolts and nuts, first having been passed down over the up-

130

per end of rod A, embracing A and the two flat surfaces of B. It will be noticed from the above that only a wrench and screw-driver are required to attach this device to the pump, 5 making it extremely convenient.

Operation: The operation of the device is as follows: In Fig. 12 the hand-lever of the pump is shown in a position somewhat below the upper limit of stroke of its upper end, 10 the lower couplings C and D being coupled to the pump-rod A and the upper coupling B being uncoupled from the slide I, as shown in Figs. 16 and 14, respectively. If now the hand-lever be moved so that its upper end 15 moves still farther upward, it will carry with it the parts G and D and by means of them the pump-rod A. As the upper end of hand-lever approaches the guide z the shoulder of C at C⁴ (see Figs. 6 and 12) will come in contact with the inner surface of the guide z and the lower end of C will be forced toward the back edge of rod A, carrying lower part of 20 stirrup D from the side x, Fig. 4, of lower part of slot A⁴ at A⁵ to the opposite side or edge of the slot. The relative position of the parts are now shown in Fig. 17, with stirrup D uncoupled from rod A, which latter is now free to either remain stationary or drop by its weight and that of the water in the pump; 25 so that if the hand-lever is moved still farther in the same direction stirrup D, the arm of which has pressed out the arm B at B⁵, moves up and out of contact with the point B⁵, allowing coupling-arm B to move toward rod 30 A from the tension of spring E, causing the lug B² to pass through the hole A³ in rod A and engage the mortise I⁵ in slide I if I⁵ registers with B². If I is at such a position that I⁵ does not register with B², arm B being acted 35 upon by spring E tends to force lug B² through opening A³ in rod A and engage I⁵ in I as soon as I reaches such a position that I⁵ does register with B².

In the construction of slide I it is formed 45 with a beveled lower end at I⁶. The object of this is to allow this slide I to slide down over the lug B² of arm B when B² extends through A³ and projects from the surface of rod A without damage or jar to the lug B². 50 If the adjustment of length of stroke of the windmill-rod and the position of the slide on the rod is such that when the pump-rod is released by the hand-lever at highest point of stroke of pump-rod the lug B² is left at a 55 point higher than the highest point reached by recess I⁵ in I, the beveled recess I⁴ will engage lug B² of arm B as slide I moves downward, forcing rod A, by means of arm B, down to a point where B² is below the highest 60 point reached by recess I⁵, so that B² must register with and engage I⁵ upon the next upward stroke of slide I when moved by the windmill-rod. If now, the hand-lever being uncoupled from the pump-rod A, it is desired 65 to couple the hand-lever to rod A and uncou-

ple the windmill-rod, the lower end of the hand-lever is raised and the upper end is thereby lowered. The arm of stirrup D which is on the side next to arm B (as soon as upper end of hand-lever is carried far enough downward) engages the inclined surface B³ of arm B, and a continuance of this motion causes the lower end of arm B to be forced away from rod A, causing lug B² to be withdrawn from recess I⁵ in slide I, thus uncoupling the windmill-rod from rod A. A continuance of this motion of the upper end of hand-lever causes stirrup D to move downward in slot A⁴ until the inclined face of the hook C² at the lower end of lower coupling-arm C is 80 reached, when arm C will be forced toward back edge of rod A until stirrup D registers with the opposite notched side A⁵, when stirrup D, by means of the spring C³ pressing on the front edge of rod A, will cause stirrup D 85 to engage the notch A⁵, so that the hand-lever is now coupled to the pump-rod A. This coupling cannot fail to be made, as rod A, if free to move, must be prevented from dropping too far by the buffer F and the spring H. 90

It will be noticed from the above-described operation of the device that it is impossible for the windmill-rod and hand-lever to be coupled to the pump-rod at the same time, as from the construction of the parts one coupling is entirely disconnected from the pump-rod before the other coupling is connected to the pump-rod, and vice versa. This obviates accidents to the device and to those using it, 95 which is a valuable feature. 100

Having thus described my invention, what I claim as new, and desire to secure by Letters Patent, is—

1. In a windmill-pump coupling, the combination of a pump-rod having at its upper end a rabbet A' and slot A² and a locking-opening A³ below, the upper coupling-arm B having a cross-head B' at its upper end fitting the slot and rabbet at the upper end of the pump-rod and a locking-lug B² adapted to engage the opening A³, the windmill-slide having locking-recess I⁵ also adapted to be engaged by said lug, a hand-lever and means for enabling it to operate upon the upper coupling-arm, substantially as shown and described. 115

2. In a windmill-pump coupling, the pump-rod having a longitudinal slot A⁴ with lateral enlargement or locking-seat A⁵ at the bottom, a recessed side A⁶ and a notch A⁷; in combination with the lower coupling-arm C pivoted at its upper end to said rod in the recessed side and having an inclined edge C⁴ and at its lower end a hook C², a spring for giving lateral movement to the arm about its pivot, a hand-lever with pintle-pin, a stirrup hung upon said pin and sliding in the slot A⁴ of the pump-rod and adapted to engage the locking-seat A⁵ to connect the hand-lever to the pump-rod, substantially as shown and described. 130

3. In a windmill-pump coupling, the upper coupling-arm B having a swinging connection for the pump-rod at its upper end, a lug B² near the middle and a curved lower end B³B⁴; 5 in combination with the pump-rod, the windmill-rod slide, a spring for pressing said arm toward the pump-rod, a lower coupling for the pump-rod, a hand-lever, and means for operating said arm by the hand-lever, substantially as shown and described. 10
4. In a windmill-pump coupling, the combination of the pump-rod having a transverse bolt-seat A⁸, a buffer F having a hole through it to receive the pump-rod and also a bolt-hole 15 and two laterally-projecting guide-lugs, a bolt connecting the buffer to the pump-rod, a supporting-spring for the buffer mounted on the pump-head, an upper coupling-arm for the windmill-rod having its lower end guided between the lugs of the buffer and a spring connecting the lower end of said arm to the buffer, substantially as shown and described. 20
5. In a windmill-pump coupling the combination with the pump-rod and the windmill-rod; of an intermediate connecting-slide having a take-up adjustment at its upper end, a longitudinal channel for the pump-rod, a locking- 25
- seat I⁵, a notch I⁴, an inclined end I³ and guide-flanges I⁶ I⁷, an upper coupling-arm arranged between said flanges, and means for operating it substantially as shown and described. 30
6. In a windmill-pump coupling, the combination of a slide for the windmill-rod, a slotted pump-rod, and an upper coupling-arm having a locking-lug, the pump-rod being between the said slide and locking-arm and the lug of the coupling-arm being arranged to pass through the pump-rod and into the windmill-rod slide to couple these parts together, substantially as described. 35
7. In a windmill-pump coupling, the combination of a hand-lever having a forked end, a pintle-pin with notches G', and serrated and adjustable nut G², the stirrup D hung upon said pin, a pump-rod having a longitudinal slot 40 with locking-seat, the notches G' of the pintle-pin fitting the edges of the slot of the pump-rod and the stirrup being arranged to play in said slot, substantially as and for the purpose described. 45
